(57) **CLAIM**

The ornamental design for a hand tool, as shown and described.

DESCRIPTION

FIG. 1 is a perspective view of a hand tool showing one embodiment of my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of a hand tool showing a second embodiment of my new design;

FIG. 9 is a front elevation view thereof;

FIG. 10 is a back elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a perspective view of a hand tool showing a third embodiment of my new design;

FIG. 16 is a front elevation view thereof;

FIG. 17 is a back elevation view thereof;

FIG. 18 is a left side elevation view thereof;

FIG. 19 is a right side elevation view thereof;

FIG. 20 is a top plan view thereof; and,

FIG. 21 is a bottom plan view thereof.

It is understood that the line shading pattern on the front and rear surfaces of embodiments 2 and 3 represent a brushed metal surface.

The broken lines shown in the drawings are for illustrative purposes only and form no part of the claimed design.

UNITED STATES PATENT AND TRADEMARK OFFICE
CERTIFICATE OF CORRECTION

PATENT NO. : Des. 527,963 S
APPLICATION NO. : 29/238950
DATED : September 12, 2006
INVENTOR(S) : John Hermann

Page 1 of 8

It is certified that error appears in the above-identified patent and that said Letters Patent is hereby corrected as shown below:

Title page showing the illustrative figure 1 should be deleted and replaced with the attached replacement figure 1.

Drawing sheets, consisting of Figs. 1, 2, 3, 8, 9, 10, 15, 16 and 17 should be deleted and replaced with the drawing sheets consisting of Figs. 1, 2, 3, 8, 9, 10, 15, 16 and 17, as shown on the attached replacement figures.

Signed and Sealed this

Fifth Day of December, 2006

A handwritten signature in black ink, appearing to read "Jon W. Dudas", is placed over a dotted rectangular background.

(57) **CLAIM**

The ornamental design for a hand tool, as shown and described.

DESCRIPTION

FIG. 1 is a perspective view of a hand tool showing one embodiment of my new design;
FIG. 2 is a front elevation view thereof;
FIG. 3 is a back elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is a perspective view of a hand tool showing a second embodiment of my new design;
FIG. 9 is a front elevation view thereof;
FIG. 10 is a back elevation view thereof;
FIG. 11 is a left side elevation view thereof;
FIG. 12 is a right side elevation view thereof;
FIG. 13 is a top plan view thereof;
FIG. 14 is a bottom plan view thereof;
FIG. 15 is a perspective view of a hand tool showing a third embodiment of my new design;
FIG. 16 is a front elevation view thereof;
FIG. 17 is a back elevation view thereof;
FIG. 18 is a left side elevation view thereof;
FIG. 19 is a right side elevation view thereof;
FIG. 20 is a top plan view thereof; and,
FIG. 21 is a bottom plan view thereof.

It is understood that the line shading pattern on the front and rear surfaces of embodiments 2 and 3 represent a brushed metal surface.

The broken lines shown in the drawings are for illustrative purposes only and form no part of the claimed design.
